UNITED STATES PATENT OFFICE.

DENNIS PARKS, OF ST. LOUIS, MISSOURI.

MACHINE FOR SLICING AND GOUGING HEEL-BLANKS.

1,212,807.

Specification of Letters Patent. Patented Jan. 16, 1917.

Application filed July 22, 1915. Serial No. 41,316.

To all whom it may concern:

Be it known that I, DENNIS PARKS, a citizen of the United States, residing in the city of St. Louis and State of Missouri, have invented new and useful Improvements in Machines for Slicing and Gouging Heel-Blanks, of which the following is a specification.

This invention relates to the art of heel building, and has for its general object to provide a machine for slicing heel-blanks to give them the proper "set" or incline, and for gouging or concaving the under side of the heel-blank to facilitate imparting the proper seat-curvature thereto by the compress.

Stated more in detail, objects of the invention are to provide a machine of the character described having mounted therein a gouger and a slicer, with means for automatically passing heel-blanks over said gouger and slicer; to provide pushers, or feeders for forcing the heel-blanks into contact with and over the gouger and slicer, and means for producing continuous reciprocation thereof; and to provide clamps which are automatically actuated to successively clamp, and release the heel-blanks.

In the preferred embodiment of the invention I fixedly secure near opposite ends of a frame, or bed, a slicer and a gouger, respectively, and adjacent to each of these latter a support for receiving the heel-blanks.

Coöoperating with the gouger and slicer are a pair of heel-blank feeders, which are continuously and simultaneously reciprocated, so that as one feeder is moving toward the slicer the other feeder will be moving away from the gouger. Also coöoperating with said slicer and gouger, respectively, are two clamping members which are simultaneously actuated in alternation to clamp first the heel-blanks and hold them firmly in position while the feeder forces the heel-blank over said slicer or gouger, and then to release the heel-blank.

The clamping members are pivotally mounted on the reciprocating feeders, and are operatively connected in such manner that the positive actuation of one clamping member in a direction to clamp a heel-blank will simultaneously move the other clamping member in the opposite direction to release a heel-blank. Preferably also the arrangement is such that the driving mechanism

for reciprocating the heel-blank pushers also actuates the clamping members.

This arrangement is very economical, as it permits a single driving mechanism to operate what would otherwise constitute two distinct machines, viz., a machine for slicing heel-blanks and a machine for gouging heel-blanks; so that while but a single or unitary machine is employed, such machine will accommodate two operators, if desired, one operator supplying the heel-blanks to the slicer and the other operator supplying the sliced heel-blanks to the gouger. It is needless to say, however, that if preferred a single operator could be employed on the machine, who would then first use the machine in slicing the heel-blanks, and then taking a position at the opposite end of the machine, would supply the sliced heel-blanks to the gouger. I wish it understood, however, that so far as the novel manner of effecting the slicing and gouging of the heel-blanks is concerned, the invention is not restricted to having the slicer and gouger embodied in one machine, and operated from a single driving mechanism, but that the same principle of operation could be followed by having separate machines independently driven for the slicer and gouger.

Heretofore, in building heel-blanks of any considerable height, it has been customary to insert a tapered lift about midway of the height of the heel in order to give the lower portion of the heel a slight forward pitch. In building heel-blanks with the machine heretofore invented by John E. Mitchell and myself, and embodied in an application for patent filed November 2nd, 1914, Ser. No. 869,740, these tapered lifts were at first cut and embodied in the heel-blank in the same manner as the straight lifts. It was found in practice, however, that there was a frequent tendency of the freshly pasted lifts superimposed upon this tapered lift in the holder to "slide" over the tapered lift under the pressure of the ejector, resulting in the formation of an imperfect heel-blank. It was also found necessary to insert a reversely-inclined metal plate between adjacent heel-blanks in order to straighten the column of heel-blanks in the holder. It is also customary to concave the last or top lift of a heel-blank in order to enable the proper seat-curvature to be imparted to the top of the heel-blank in the compress with-

out the use of an impracticable degree of pressure.

Special machines are employed for cutting the inclined strips from which the tapered lifts are cut, and for forming a 5 ⁷⁰ ⁷⁵ ⁸⁰ ⁸⁵ ⁹⁰ ⁹⁵ ¹⁰⁰ ¹⁰⁵ ¹¹⁰ ¹¹⁵ ¹²⁰ ¹²⁵ ¹³⁰ ¹³⁵ ¹⁴⁰ ¹⁴⁵ ¹⁵⁰ ¹⁵⁵ ¹⁶⁰ ¹⁶⁵ ¹⁷⁰ ⁵⁷⁴⁰ ⁵⁷⁴⁵ ⁵⁷⁵⁰ ⁵⁷⁵⁵ ⁵⁷⁶⁰ ⁵⁷⁶⁵ ⁵⁷⁷⁰ ⁵⁷⁷⁵ <

formed integral with, one end of the push-bar 32 is a plate 35 provided at its outer side with a curved, flanged guide 36 which terminates adjacent to the side of the plate 26 and 5 of the slicer 27. Adjustably mounted on the upper side of the carriage 30 is a stop plate 36^a provided at its inner end with an up-standing flange 37^a. Said stop plate is laterally adjustable through the medium of a 10 thread bolt 38^a on the carriage 30 passing through a slot 39^a of said stop plate and having a jam-nut thereon. The flange 37^a acts as a stop to arrest the movement of the heel-blanks as they are placed in the machine by 15 the operator to be sliced.

Still referring to the portion of the machine illustrated at the left of Figs. 1 and 2, the numeral 37 indicates a yoke lever which spans the carriage 30 and is provided at opposite ends with legs 38 which are pivotally mounted at 39 intermediate their ends on the inner end of the carriage 30. The lower ends of the legs 38 are pivotally connected to the outer ends of the respective drive-rods 25 19 and 21, as indicated at 40. Projecting outward from the center of the yoke-lever 37 is an arm 41 in which is adjustably mounted a clamping-member 42, said clamping-member having a screw-threaded shank 30 43 extending through a slot 44 in the arm 41, and being provided with a jam-nut 45 and an adjusting nut 46, by manipulating which, in a well-understood way, the clamping-member 42 may be adjusted vertically and 35 laterally in the arm 41. Journaled in the lower ends of the legs 38 and extending between the same is a rod 47, the outer ends of which constitute the pivots 40 for the respective drive rods 19 and 21. Projecting 40 downward from the carriage 30 at opposite sides thereof, respectively, are two lugs 48, each of which is bifurcated to provide an elongated recess 49 (Fig. 4), which spans the rod 47 and in which the latter has a 45 limited movement.

Referring now to the construction illustrated at the right of Figs. 1 and 2, a plate 50, corresponding to the plate 22, has mounted thereon a gouge 51, the cutting edge of which is curved; and a carriage 52, similar to the carriage 30, has adjustably mounted thereon a push-bar 53 provided with a guide 54, and opposite the guide an adjustable stop-plate 55. A yoke-lever 56 50 carrying a clamping-member 57 and having a rod 58 connecting the lower end of its legs is pivotally mounted on the carriage 52 exactly in the same manner as the yoke-lever 37 is mounted on the carriage 30. Bifurcated lugs 59 project downward from the under side of the carriage 52 and span the rod 58, which has a limited movement in said lugs, the latter corresponding exactly in construction and function with the lugs 60 48 before referred to. The rods 47 and 58

are connected by rods 60 which are located at opposite sides of the machine and are pivotally mounted at their opposite ends on the said rods 47 and 58. The push-bar 53 is provided at its center with a curved, upwardly-extending portion 61 to enable the push-bar to pass over the gouge 51 in the operation of the machine. This operation is as follows: The pulley 12 being rotated, the shaft 11 will be operated to continuously rotate the gear 16 and crank disk 17 from the gear 14. This rotation of the shaft 11 causes the continuous reciprocation of the driving rods 19 and 21. As these rods move outward, or toward the end of the machine at 70 the left of the drawing, the rod 47 will first be moved from the inner to the outer edges of the slots 49. During this movement the lower ends of the legs 38 will be moved outward, thereby throwing the yoke-lever 37 75 inward and raising the clamping-member 42. When the rod 47 engages the outer edges of the slots 49 in the lugs 48 the carriage 30 will then be moved outward on the rods 1 and 2 to the extreme limit of the throw of 80 90 the driving rods 19 and 21.

Assuming, now, a heel-blank X to have been placed by the operator in position against the stop 37^a and the inner edge of the push-bar 32, such heel-blank will then 95 have the position shown in Fig. 4, its rear or curved edge resting upon the cutting edge 28 of the slicer 27. As the driving-rods 19 and 21 move rearward, the first result of such motion is to draw the lower ends of 100 the legs 38 inward and thereby throw the yoke-lever 37 outward and turn the clamping-member 42 into engagement with the top of the heel-blank X, as shown in Fig. 4. The rod 47 now engages the inner edges of 105 the slots in the lugs 48 which engagement will cause the carriage 30, the push-bar 32 and the yoke-lever 38 to move inward. In this movement the heel-blank X will be forced against the cutting edge of the slicer, 110 which will operate to cut a slice of leather from the heel-blank. The line of cut will be on an inclined path relative to the plane of the upper side of the heel-blank, owing to the fact that the heel-blank is held in an 115 up-set position by reason of its curved edge resting upon the slicer 27, which latter occupies a plane slightly above the plane of the support 6. The movement of the heel-blank over the slicer is, of course, caused by 120 the engagement of the push-bar 32 with the breast of the heel, and during the entire inward movement of the carriage 30 the heel-blank will be held firmly in the position shown in Fig. 4 by reason of the pressure 125 thereon of the clamping-member 42. The operations occurring at the right-hand side of the machine, in connection with the gouger 51, are the same as those just described, with the exception that the rod 58 130

is not actuated directly by the driving rods but through the medium of the connecting rods 60 so that the carriage 52 moves inward as the carriage 30 is moving outward. In 5 this latter movement of the carriage 30 the rod 58 will first be moved to turn the yoke-lever 56 downward so that its clamping-member will engage the heel-blank which has been placed in position on the gouger, 10 as shown by dotted lines, and then the engagement of the rod 58 with the inner edges of the slots in the lugs 59 will cause the carriage 52, the push-bar 53 and the yoke-lever 56 to be drawn inward, the said push-bar 15 forcing the heel-blank against the gouger which operates to form a concave in the heel-blank by removing a circular portion of material therefrom from near the outer edge to the breast of the heel-blank. A 20 heel-blank thus sliced and gouged, when compressed in the usual way, will be found to have the requisite set and concave, and these characteristics are imparted to the heel-blank in such manner as to secure accuracy in result and with the use of a machine extremely simple in organization and 25 operation. Furthermore, the use of a skilled mechanic is not required in performing these actions, as any unskilled person may soon 30 acquire great facility in placing the heel-blanks in position on the gouger or cutter after each outward movement of the respective push-bars.

I claim:

35 1. In a machine of the class described, a stationary cutter, means for supporting an independent heel-blank with its upper flat side in inclined relation thereto, and with a portion extending across the plane of the 40 cutter, and a reciprocable member for forcing the heel-blank in a right line into contact with and over said cutter.

2. In a machine of the class described, a cutter, means for supporting a heel-blank 45 with its upper flat side in inclined relation thereto and with a portion extending below the plane of the cutter, means for automatically clamping the heel-blank in such position, and means for effecting relative 50 movement between the heel-blank and the cutter in a horizontal plane while the heel-blank is held in its clamped position.

3. In a machine of the class described, a stationary cutter, means for supporting a 55 heel-blank in an inclined position relative thereto, means for advancing the heel-blank in a right line toward said cutter, a clamp movable with said advancing means for holding the heel-blank in a fixed position 60 while being advanced, and means for automatically releasing said clamp.

4. In a machine of the class described, a stationary cutter, a support for heel-blanks located below the plane of said cutter a distance 65 equal to the thickness of the material

to be cut from the heel-blank, a pusher for forcing the heel-blank toward the cutter, a clamp movable with the pusher for holding the heel-blank in fixed position during its movement toward the cutter, and means for simultaneously moving said clamp and pusher. 70

5. In a machine of the class described, a cutter, a support for heel-blanks located below the plane of said cutter, a movable 75 pusher located above said support and adjustable to permit a heel-blank to rest on said support only when one edge portion of said heel-blank rests on said cutter, heel-blank clamping means movable with said 80 pusher, and means for reciprocating said pusher toward and from the cutter.

6. In a machine of the class described, a cutter, a support for a heel-blank located below the plane of said cutter, a slidable 85 carriage, a heel-blank pusher carried thereby, a pivoted clamp mounted on said carriage, and actuating means operating in one stage of movement first to turn said clamp into engagement with a heel-blank and then 90 to move said carriage in a direction to cause said pusher to force the clamped heel-blank into contact with said cutter, and in the next stage of movement first to release said clamp and then to return said carriage to its normal 95 position.

7. In a machine of the class described, in combination with a slicer and a gouger oppositely disposed with respect to each other, means for supporting heel-blanks in operative relation to said slicer and gouger, heel-blank pushers movable toward and from said slicer and gouger, respectively, a pivoted clamping member movable with each pusher, driving mechanism connected to one of said clamping members, means connecting the two clamping members whereby they will be moved simultaneously in opposite directions, and a lost-motion connection between the respective clamping-members and pushers whereby each clamp will in turn be operated in advance of the movement of the pusher. 100 105 110

8. In a machine of the class described, in combination with a slicer and a gouger oppositely disposed with respect to each other, heel-blank advancing members operatively associated with said slicer and said gouger, respectively, heel-clamps operable to engage heel-blanks deposited in front of said advancing members, and means for continuously reciprocating said heel-blank advancing members and for actuating each clamp alternately to clamp and release a heel-blank in advance of the movement of its advancing member toward and from the slicer and gouger, respectively. 115 120 125

9. In a machine of the class described, in combination with a slicer and gouger oppositely disposed with respect to each other, 130

- slidable carriages coöperating, respectively, with said slicer and gouger, a clamp pivotally mounted on each of said carriages, means connecting said clamps, driving 5 mechanism for actuating one of said clamps, a lost-motion connection between each of said clamps and its carriage, and a heel-blank advancing member carried by each carriage.
10. In a machine of the class described, in combination with a slicer and gouger oppositely disposed with respect to each other, heel-blank pushers coöperating with said slicer and said gouger, respectively, a heel-blank clamp movable with each pusher, and actuating means operating alternately to move each clamp to clamping position, then to advance the corresponding pusher toward the slicer or gouger, and then to release said 20 clamp and return the pusher to normal position.
11. In a machine of the class described, in combination with a slicer and a gouger oppositely disposed with respect to each other, slidable carriages mounted in operative relation to said slicer and gouger, respectively, a yoke-lever pivotally mounted intermediate the ends of its legs on each carriage, rods connecting the corresponding 30 ends of said legs, a lost-motion connection between each carriage and its yoke-lever, a clamping member carried by each yoke-lever, a heel-blank pusher carried by each carriage, and driving mechanism connected 35 with one of said yoke-levers.
12. In a machine of the class described, a stationary cutter, a slidable carriage mounted in operative relation thereto, a push-bar adjustably mounted on said carriage and located above said cutter, means for supporting a heel-blank on said carriage with its top in operative relation to said cutter and its breast engaged by said push-bar, and means for reciprocating said carriage.
- 40 13. In a machine of the class described, a cutter, a slidable carriage mounted in operative relation thereto, a lever pivotally mounted on said carriage, a clamping-member adjustably mounted in said lever, means
- for supporting a heel-blank in operative relation to said cutter, a heel-blank pusher mounted on said carriage, and means for actuating said lever to clamp the heel-blank and for moving said carriage to cause its 55 pusher to force the clamped heel-blank into contact with said cutter.
14. In a machine of the class described, in combination with a slicer and a gouger oppositely disposed with respect to each other, heel-blank pushers and heel-blank clamps operatively positioned with respect to said gouger and slicer, driving mechanism, and means actuated thereby for operating first one of said clamps to engage a heel-blank 60 and then to advance a corresponding pusher to force the heel-blank into contact with the slicer or gouger, and then to release said clamp and return the pusher to normal position while simultaneously operating the 65 other clamp and pusher in the reverse manner.
15. In a machine of the class described, in combination with a stationary cutter, a slidable push-bar movable in a horizontal 70 plane above the cutter, a support for a heel-blank located below said cutter, an adjustable stop coöperating with said push-bar to position a heel-blank with respect to said cutter, and means for reciprocating said 75 push-bar.
16. In a machine of the class described, in combination with a stationary cutter, a slidable carriage mounted in operative relation thereto, a push-bar adjustably mounted on 80 said carriage, a stop also adjustably mounted on said carriage adjacent to said push-bar, and means for reciprocating said carriage.
17. In a machine of the class described, in combination with a cutter, a carriage slidably mounted in relation thereto, a push-bar adjustably mounted on said carriage, a guide plate carried by said push-bar, a stop adjustably mounted on said carriage opposite 85 said guide plate, and means for reciprocating said carriage.

In testimony whereof, I have hereunto set my hand.

DENNIS PARKS.
